UNITED STATES PATENT OFFICE

151,861

DESIGN FOR A LAMP

Abraham Troskin, Brooklyn, N. Y.

Application July 3, 1947, Serial No. 140,073

Term of patent 14 years

(Cl. D48—20)

To all whom it may concern:

Be it known that I, Abraham Troskin, a citizen of the United States of America, residing in the Borough of Brooklyn, city of New York, county of Kings, and State of New York, have invented a new, original, and ornamental Design for a Lamp, of which the following is a specification, reference being had to the accompanying drawing, forming part thereof.

I claim:

The ornamental design for a lamp, as shown.
ABRAHAM TROSKIN.
